UNITED STATES PATENT OFFICE.

CLARENCE D. HAMMON, OF DELAVAN, MINNESOTA.

TIRE-TIGHTENER.

SPECIFICATION forming part of Letters Patent No. 397,982, dated February 19, 1889.

Application filed April 2, 1887. Renewed August 27, 1888. Serial No. 283,935. (No model.)

To all whom it may concern:

Be it known that I, CLARENCE D. HAMMON, of Delavan, in the county of Faribault and State of Minnesota, have invented certain new and useful Improvements in Tire-Tighteners, of which the following is a specification.

My present invention relates to tire-tighteners; and the invention consists in certain features hereinafter more fully set forth and claimed.

Figure 1 is a perspective view. Fig. 2 is a top plan view with a portion broken away, and Fig. 3 is a sectional view on the line *xx* of Fig. 2.

This invention is designed for use in the same manner or for the same purpose as that described in my patent, No. 347,347, but differs therefrom in several particulars.

In Fig. 1, *F* represents a portion of the rim or felly of a wheel, and *R* a spoke of the same. The clamp by which the device is fastened to the spoke consists of a block, *A*, having a solid head at one end, in which is cut a female screw-thread for the reception of screw *c*, as shown, the block *A* having two laterally-projecting arms, *n n*, to embrace the spoke and hold the clamping devices. I then provide a clamping-block, *B*, having in its opposite faces concavities of differing sizes, as shown in Figs. 1 and 2, to adapt it to spokes of different sizes. This block *B* has projections *o* at each end, both above and below, to fit over the arms *n* of the block *A*, as shown clearly in Fig. 1, to hold it from falling out and permit it to slide to and fro on the arms *n*.

Near the outer end of the arms *n* they are provided on their inner faces with vertical recesses *w*, as shown in Fig. 2, to receive and hold a nut, *V*, made in the form of a rectangular plate, with lips *u* at its upper corners, to rest on the arms *n* and prevent it from dropping through. To this nut or plate *V* is fitted a screw, *T*, the inner end of which is rounded and bears against the clamping-block *B*, as shown in Figs. 2 and 3, this screw *T* being provided with a squared head for the application of a wrench, and which may also have a series of holes, *m*, to enable it to be turned by means of a small rod instead of a wrench, if desired.

The screw *C*, which works in the head of

block *A*, is also squared near its upper end, as shown at *J'*, and is in like manner provided with holes *m'*, so it can be turned with a wrench or a rod, as may be preferred. Instead of the bifurcated push-block used in my former patent, I use a block, *I*, made concave on its upper face where it bears against the felly *F*, as shown in Fig. 1, it having a recess at the center, as shown more clearly in Fig. 2, for the head or end of the screw *C* on which it is swiveled, the bearing-surfaces being at opposite sides of this central recess, so that the end of the rod *C* where it projects through the block *I* will not come in contact with the felly and mar it when the screw is turned. The manner of using the device is the same as in the former case, and will readily be understood by a glance at Fig. 1.

By this construction I dispense with the ratchet and pawl and the lever formerly used, thereby simplifying and cheapening the construction of the device, and, besides, it is adapted to all sizes of wheels. When it is to be used on a wheel having large spokes, the block *B* has its larger concavity placed next to the spoke, as shown in Fig. 1, and made to clasp the spoke tightly between it and the concave face of the head or block *A*; but when it is desired to use it on a wheel having smaller spokes, then the nut *V* is lifted out, the plate *B* slipped off, turned around and slipped on, and the nut *V* dropped back in its seat, and the smaller concave of the block *B* is then forced against the spoke by means of the screw *T*. As the push-block *I* in this has no arms to straddle the spoke as before, and is made broad enough on its concave face to fit any-sized felly, it can be applied to the lightest carriage-wheel or to the heaviest wagon-wheel with equal facility. I also make the screw *C* much shorter than in my former patent, as it only needs to be turned but little to raise the felly sufficiently to insert the washer between it and the shoulder of the spoke, and thus it is rendered more portable, occupying but little space in a wagon.

Having thus described my invention, what I claim is—

1. The clamp consisting of the block *A*, provided with the arms *n n*, having recesses *w*, the sliding block *B*, provided with the

projections *o*, to hold it in place on the arms *n*, and the detachable nut *V*, provided with the screw *T*, all arranged to operate substantially as and for the purpose set forth.

5 2. In a tire-tightener, a clamp for securing the device to a spoke, provided with a reversible clamping-block, *B*, having concavities of different sizes in its opposite faces, and the detachable nut *V*, provided with a screw, *T*, all arranged to operate substantially as shown and described.

3. The combination, in a tire-tightener, of the clamp consisting of the bifurcated concave block *A*, with the concave movable block *B*

and screw *T*, with the screw-rod *C*, provided 15 with a square or holes for turning it, and the concave push-block *I*, swiveled upon the end of the same, all arranged to operate substantially as described, whereby the device can be held upon a spoke without bruising the 20 same, and the spoke be forced to its seat in the hub with the same degree of force that is used to raise the felly from the spoke.

CLARENCE D. HAMMON.
